UNITED STATES PATENT OFFICE.

EARL F. BALDWIN, OF GARDNER, MASSACHUSETTS, ASSIGNOR TO AMERICAN FIBRE CORPORATION, OF GARDNER, MASSACHUSETTS, A CORPORATION OF MASSACHUSETTS.

WINDING MECHANISM.

Original application filed February 3, 1922, Serial No. 533,799. Divided and this application filed July 1, 1925. Serial No. 40,808.

This invention relates to winding mechanisms particularly designed for winding flat braid and by which the braid is caused to be wound evenly on a reel. More particularly the mechanism is designed to wind braid made from fiber strands on the machine disclosed and claimed in my application for patent, Serial No. 533,799, filed February 3, 1922, of which the present application is a division.

For a more complete understanding of this invention, reference may be had to the accompanying drawings in which

Figure 1 is a fragmentary top plan of the braiding machine showing the braid guiding and feed mechanism.

Figure 2 is an elevation of the upper portion of the mechanism shown in Figure 1.

Figure 3 is a section to an enlarged scale 20 on line 3—3 of Figure 1.

Figure 4 is an elevation of the winding mechanism.

Figure 5 is an elevation at right angles to Figures 2 and 4 showing the braid guiding, feeding and winding mechanisms in 25 their assembled relation on the machine.

Figures 6 and 7 are detail sections on lines 6—6 and 7—7, respectively, of Figure 4.

The strands to be braided are carried by 30 spools which are moved about each other to effect a braiding action, all as more fully shown and described in my application for patent hereinbefore referred to. All the strands pass from the spools to a guide member 120 (Figures 1, 3 and 5) at which the actual braiding takes place. This member is supported on a transverse bar 121 carried at opposite ends in standards extending upwardly intermediate the length of 35 the machine only one of which, composing side rails 145 and a cross bar 123, is shown in the drawings and is carried by a sleeve 124 adjustable along the bar 121. This sleeve has an upstanding guide portion 125 40 in which is vertically slidable a plate 126, a bolt 127 carried by the portion 125 and passing through a vertical slot in the plate 126 providing for such slidable adjustment. The plate 126 has fast thereto a frame member or yoke 127 to the upper end of 45 which is pivoted by a lateral extension 128 a similar member 129. Each of these members carries a roller 130 at its lower end.

The rollers 130 are normally held together into close engagement with the various 55 strands forming the braid by means of a cam device shown more in detail in Figures 1 and 3. This device comprises a cam 132 pivoted at 133 to the outer end of a rod 134 which extends through the members 127 and 129 and carries a nut 135 beyond the member 127 to hold it in position. Between the members 127 and 125 a coil spring 136 reacts, this spring surrounding the rod 134. The cam member 132 is formed with a cam 60 face 137 which engages the outer face of the yoke 129 and is provided with a handle portion 138 by which it may be turned into and out of camming relation to this yoke. When the cam is in camming relation the 70 rolls 130 are held near to each other by the cam 132 and the spring 136, the spring pressing the rolls slightly apart against the cam which imposes a positive limit to the separation and keeps the rolls closely adjacent 75 to each other, but when the handle 138 is pulled outwardly the spring 136 forces the yoke members further apart to relieve the pressure on the braid. The distance between the rolls, when the cam is in camming relation, is determined by the position of the nut 135 on the rod 134 and is preferably adjusted according to the weight of the material braided to pinch the braid 80 firmly and flatten it. The braid passes over the rollers 130 and to a driven take-up mechanism supported by the post 123. This mechanism comprises a series of rolls 140, 141, and 142, each roll preferably having a central portion which engages the braid 85 formed of yieldable material such as rubber as shown at 143. The braid passes over the upper roll 140 beneath and between this roll and the roll 141 and then between the rolls 141 and 142, this causing an engagement of 90 the surfaces 143 over a considerable length of the braid so as to increase the frictional holding of the rolls thereon. These rolls are positively driven, intermeshing gears 144 at each end of these various rolls being 95 employed for this purpose. The upper roll 140 has fast thereto outwardly of a pair of spaced rails 145 in which the rolls are journaled, a gear 146 which is driven from a pinion 147 carried by a shaft 148 on the opposite end of which is fixed a worm gear 100 105

149. This worm gear meshes with a worm 150 on a vertically extending shaft 151 journaled in a bearing bracket 152 projecting laterally from the one of the side pieces 5 145. This shaft carries at its lower end a gear 153 which meshes through a change gear 154 with a driving gear 70.

After passing between the lower rolls 141 and 142 the braid passes through a guide 10 eye 160 in a guide bar 161 (Figure 4). The guide bar 161 is mounted to slide in a pair of arms 162 and 163 which project upwardly from a bracket 164 made fast to one side of the frame. These arms 162 and 163 have 15 journaled therein a shaft 165 which projects beyond the arm 163 and has fixed thereto a belt pulley 166 and carries a winding reel 167. A belt indicated at 168 passes about this belt pulley 166, is crossed intermediate 20 its length and passes over a pulley 169 mounted to rotate with the roll 140.

Provision is made by which the bar 161 is moved parallel to the shaft 165 in order to guide the braid as it is wound from one 25 end to the other of the reel. For this purpose the bar 161 has in one face thereof a groove 170, this groove being in the form of an elongated loop extending lengthwise of the bar and within this loop is fixed a 30 series of pins 171 extending outwardly from the face of the bar, these pins being spaced to mesh with a pinion 172. This pinion is carried by a shaft 173 having its end 35 174 shaped to fit within the groove 170 to be guided for traversing movement thereby. The shaft 173 is fixed within the end of a shaft 174^a, these two shaft members constituting a transmission shaft which is journaled in a yoke 175, the arms 176 of which 40 are mounted for rocking movement on the drive shaft 165 between the arms 162 and 163. Within this yoke the shaft 174^a has fixed thereto a bevel gear 177 which meshes with a bevel pinion 178 fixed to the shaft 45 165. By this construction, as the shaft 165 is rotated the gear 177 is rotated, causing a transverse movement in opposite directions of the bar 161 by engagement of the pins 171 with the teeth of the pinion 172. 50 As the bar 161 traverses, the gear 172 is held in engagement with the pins 171 by the end of the shaft 174 engaging in the slot 170. As it reaches the end of traverse in one direction the portion 174 riding in 55 the slot 170 causes the yoke 175 to tilt slightly about the shaft 165 as an axis and as the pinion 172 rotates about the end pin of the series it starts the traverse of the bar 161 in the opposite direction. This is 60 illustrated in Figure 7 in which the positions of the pinion 172 with relation to the bar are shown in dotted lines when shaft 174 engages in upper and lower reaches of the looped groove, these being the positions 65 in which the bar is traversed in opposite

directions. By this construction the braid is led evenly throughout the length of the reel 167 as it is wound thereon.

Having thus described an embodiment of this invention it should be evident that 70 many changes and modifications might be made therein without departing from its spirit or scope as defined by the appended claims.

I claim:

1. In a machine of the class described, mechanism for receiving strands in braided formation comprising a pair of rolls between which the strands pass, resilient means tending to separate said rolls, and 80 positive means for moving one roll toward the other and for limiting the amount of separation.

2. In a machine of the class described, mechanism for receiving strands in braided formation comprising a pair of rolls between which the strands pass, spring means tending to separate said rolls, and cam means for bringing one roll to a position closely adjacent to the other roll and 90 co-operating with said spring to hold the first said roll in said position.

3. In a machine of the class described, a frame having a roll journaled therein, a second frame hinged to said first frame and carrying a roll cooperating with said first roll to guide strand material therebetween, means normally tending to swing said frames apart to separate said rolls, and a clamp for holding said rolls closely adjacent each other.

4. In a machine of the class described, the combination with a winding mechanism of a traversing guide comprising a reciprocable bar having a strand guide eye 105 therein and a guideway on one side in the form of a closed loop, and means operatively connecting the bar with the winding mechanism, said means including a rotatable shaft having one end disposed to travel 110 in said guideway and interengaging means on said shaft and bar for causing said bar to reciprocate when said shaft rotates.

5. In a machine of the class described, a winding mechanism comprising a drive shaft, a reel carried by said drive shaft, means to rotate said drive shaft, a bar reciprocable parallel to the axis of said drive shaft and having a strand guide eye therein, and a guideway on one side in the form of 120 a closed loop, a yoke pivoted on said drive shaft, a shaft carried by said yoke transverse to said drive shaft and having its end bearing in said guideway, means for driving said yoke shaft from said drive shaft, and interengaging means on said yoke shaft and bar for causing traversing movement of said bar on rotation of said yoke shaft.

6. In a machine of the class described, a winding mechanism comprising a drive 130

- shaft, a reel mounted on said drive shaft, means for rotating said shaft, a bar having a strand guide eye therein and a guideway in one side in the form of a closed loop, a yoke pivoted on said drive shaft, a transmission shaft carried by said yoke and having its end disposed in said guideway, means operatively connecting the transmission shaft with the drive shaft, and inter-
engaging means on said transmission shaft and guide bar for reciprocating the bar
- when the shaft rotates, said means comprising a series of pins projecting from the side of the bar from the portion bounded by the looped guideway, and a pinion ¹⁶ mounted on said transmission shaft and positioned in a manner to engage the said pins.

In testimony whereof I have affixed my signature.

EARL F. BALDWIN.
